Inventor:

Frederick S. Anable

By Emery, Good, Jamey and Harvey
Attorneys.

UNITED STATES PATENT OFFICE.

FREDERICK S. ANABLE, OF BROOKLINE, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,386,675.

Specification of Letters Patent.

Patented Aug. 9, 1921.

Original application filed February 1, 1908, Serial No. 413,798. Patent No. 1,168,777. Divided and application filed January 6, 1916, Serial No. 70,554. Divided and this application filed August 23, 1918, Serial No. 251,063. Renewed January 3, 1921. Serial No. 434,863.

To all whom it may concern:

Be it known that I, FREDERICK S. ANABLE, a citizen of the United States, and a resident of Brookline, in the county of Norfolk and 5 State of Massachusetts, have invented an Improvement in Strip-Serving Devices, (Case A,) of which the following description, in connection with the accompanying drawings, is a specification, like characters 10 on the drawings representing like parts.

This application is a division of my co-pending application Serial No. 70,554, filed January 6, 1916, which itself is a division of my application Serial No. 413,798, filed February 1, 1908, now Patent No. 1,168,777.

This invention relates to devices or apparatus for supplying strips of paper or other suitable material of any desired length to be applied to packages, bottles, bundles or the 20 like as a wrapping means or as a label or for any other desired purpose, the illustrated embodiment of the invention showing an apparatus provided with means for holding a strip supply previously gummed on one side, 25 such strip being adapted to be withdrawn in selected lengths and further provided with means for moistening the gummed side of the strip as the latter is withdrawn. It is apparent that an ungummed strip of paper 30 or the like might be employed, and the moistening device be utilized for applying adhesive to the side of the withdrawn strip.

My invention will be best understood by reference to the following description when 35 taken in connection with the accompanying illustration of one specific embodiment thereof, the scope of the invention being more particularly pointed out in the appended claims.

40 Referring to the drawings,—

Figure 1 is a side elevation of a strip serving apparatus embodying my invention;

Fig. 2 is a plan view of a portion of the apparatus shown in Fig. 1; and

45 Fig. 3 is a side elevation of a modified form of the apparatus shown in Figs. 1 and 2.

In that form of the invention herein disclosed, means are provided to prevent contact of the free end of the strip of the moistener when the apparatus is not in use.

50 In the figures, the strip support therein indicated at 1 may be of any suitable char-

acter. Preferably the strip is supported in the form of a roll in a suitable casing upon 55 a base 2, there being suitable tensioning means for the roll, as, for example, a thumb nut 3. Preferably mounted upon the base 2 is a tank or reservoir 4 having operatively connected thereto any suitable moistening 60 device, herein represented as a wick 5 arranged in inverted U shape with the ends thereof depending into the tank, the intermediate portion being suitably disposed to moisten the strip as the latter is drawn 65 across the same. Any suitable strip severing means may be provided, as, for example, the blade 6 herein represented as in advance of the moistener.

I utilize means tending to elevate the free 70 end of the strip when not drawn upon. Herein I accomplish this result by employing certain guiding members between the strip support and the moistener tending, when the strip is not drawn upon, to depress a portion of the strip into the form of a bight or into U shape, whereby the free end of the strip or the leading end of the bight is elevated. Herein I employ a movable member 7 which may be in the form 75 of a roll having a concaved forward edge 8 adjacent which edge is a guiding member 9 having preferably a convex surface projecting toward the roll 7, so that the strip is transversely arched by said members 7 80 and 9.

In Figs. 1 and 2 the said member 7 is represented as mounted in slotted bearings 10 in the brackets 11, it being apparent that when the strip is drawn upon for use, the 90 member is lifted in its bearings so as to permit the strip to pass straight or substantially straight, if desired, from the guiding roll or rod 12, in the rear of said member, the member being returned in any suitable manner, as by spring 13. Either member 7 or 9 may be concaved, the other member being convex, or the member 7 may be cylindrical and the member 9 correspondingly shaped. In either event, a guiding 100 member is provided tending to be moved by draft upon the strip for use and tending after the severance of the strip to depress or to move the strip into the form of a bight, thus forming the leading end of the 105 bight as represented in Fig. 1.

In Fig. 3, a modification of this form of the invention is shown wherein the roll 14, which may be cylindrical or concaved or convex, is provided with means adapted to be impinged upon by the strip to elevate the same. Herein I have represented said roll 14 as mounted upon a bell crank lever 15, one member whereof is provided with a rod 16 interposed in the path of the strip and adapted to be depressed, thereby to elevate the roll 14 and permit the passage of the strip in more nearly a straight line. When the strip is not drawn upon, the leading end thereof is shaped into a bight between the roll 14 and the guiding members 17 and 18 adjacent thereto. If desired, the roll 14 may be arranged to be closely adjacent the rolls 17 and 18 when depressed.

Having thus described one illustrative embodiment of my invention, I desire it to be understood that although specific terms are employed, they are used in a generic and descriptive sense, and not for purposes of limitation, the scope of the invention being set forth in the following claims.

Claims:

1. A strip serving device comprising in combination, a strip support, a moistener in operative relation thereto, and means interposed between said support and said moistener to deflect the strip into a bight, and thereby to separate the leading end of the strip from the moistener, said means including a fixed guide constituting a fulcruming member for the strip and positioned adjacent the said moistener, and a movable strip guiding member between said fixed guide and the strip support and in proximity to said fixed guide.

2. A strip serving device comprising in combination, a strip support, a moistener in operative relation thereto, and means interposed between said support and said moistener to deflect the strip into a bight, and thereby to separate the leading end of the

strip from the moistener, said means including three members, two of which are fixed members, one of said fixed members being in proximity to said moistener and constituting a fulcruming member for the strip, the third member being positioned between said two fixed members and movable with respect thereto for deflecting said strip.

3. A strip serving device comprising in combination, a strip support, a fixed moistener in operative relation thereto, and means interposed between said support and said moistener to deflect the strip into a bight, and thereby to separate the leading end of the strip from the moistener, said means including three members in close proximity to each other and the leading one thereof being fixed and in close proximity to the moistener and constituting a fulcruming member for the strip, and the member next to the fulcruming member being movable downwardly to deflect the free end of the strip upwardly away from the fixed member.

4. A strip serving device comprising a strip support, a moistener in operative relation thereto, and guiding means for the strip between the moistener and its support and including two relatively movable members provided respectively with concave and convex surfaces.

5. A strip serving device comprising a strip support, a moistener in operative relation thereto, guiding means for the strip between the moistener and its support and including two relatively movable members provided respectively with concave and convex surfaces, and connections to the movable member having means adapted to be impinged upon by the strip when drawn upon for use, whereby said movable member may be separated from the adjacent member.

In testimony whereof, I have signed my name to this specification.

FREDERICK S. ANABLE.
